UNITED STATES PATENT OFFICE

PIERRE MARIUS GROSJEAN, OF ROSNY-SOUS-BOIS, FRANCE

CROSSING FOR RAILWAY TRACKS

Application filed July 7, 1930, Serial No. 466,331, and in France July 9, 1929.

The object of the present invention is a crossing for railway tracks constructed so as to fulfil the following conditions:

1°—When the crossover road is provided with crossings (single or double slip points), flexible points can be used of the same or greater length than those used with the known type of crossings.

2°—The crossing is rigidly fixed and offers great resistance to forces tending to dislocate the parts at the rail joints.

3°—A great resistance to the transverse forces exerted by the wheels of the vehicles passing over the cross-over of the track.

4°—The raised guard rail of the crossing cannot be bent out of position or inclined sidewise.

5°—The step between the top of the stock rail and the top of the raised guard rail remains always constant, and can only increase with the wear of the stock rail; in other words, there can never be an accidental step, and this allows the play in the vertical direction between the track members and the profile of the rolling material to be reduced to a minimum.

6°—The possibility of effectively guiding the wheels and bogies as they pass over a great length of the crossing, in order to reduce to a minimum the transverse oscillations of the vehicles.

The following description with the accompanying drawings, given by way of example, will enable the manner of carrying out the invention to be easily understood.

Fig. 1 shows the crossing in plan.

Figs. 2—5 are respectively sections on 2—2, 3—3, 4—4, 5—5 of Fig. 1.

Figs. 6 and 7 show how the crossing is utilized in single and double slip points.

Fig. 8 shows a detail of Fig. 6.

The crossing or frog for slip switch consists of a cast metallic member A, the metal used being any one of the special steels gen-

erally employed for crossings and the apparatus of railway cross-overs.

This member comprises:

A bent rail *a* as short as possible and a curved rail *b* (providing a transition or spiral having a large radius) which forms an integral part of the crossing, and of which the length, as shown in Figs. 6 and 8, is adapted to that of the rail *a*, so that the points or switch rails *c* and *d*, *e* and *f* can be of the same length.

In order that the crossing A should have satisfactory stability, and in order to reduce to a minimum the shocks due to the passage of the wheels over the joints, the cast member A is extended at *g*, *h*, *i*, *j* beyond the end of the bent rail *a* and curved rail *b*, so as to be able to receive the bottoms of the corresponding rails, such as *c*, *d*, *e*, *f*, *k*, *l*.

The rails that are to be connected to the frog are fixed and maintained in alignment with the rails of said frog by bolting the web of the first mentioned rails, shown in dot and dash lines (Fig. 4), to lugs such as *m*, *n*, which are also cast with the rest of the member.

These lugs *m* and *n* have, on purpose, both above and below, sufficient play between them and the head and flange of the rail, so that the position of the rail only depends on the upper faces *o* and *p* of the chairs *i* and *j* and the lateral faces *q* and *r* of the lugs *m* and *n*.

Likewise, any transverse displacement of the rails can be prevented by means of bosses *s* and *t*.

It is obvious that in the case of the use of the frog in an oblique crossing proper, that is, one not comprising a switch between the tracks which cross each other, the curved rail *b* and the member *h* *j* are not utilized.

In order to avoid any lateral deflection of the raised guard rail *u* which is constantly struck by the wheels on its face *v*, the guard rail *u* is connected to the curved rail *b* by an integral web *w* placed as high as possible.

This web can be placed at a slightly lower level than the rail *b* and prolonged towards the guard rail *u* either horizontally or inclined, so that it terminates between the shoulder *x* and the top *y* of the guard rail (Figs. 3 and 5). Apertures such as *z* can be provided in this web (Fig. 1).

The ends *c'*, *d'* of the frog point rails *a'*, *b'*, cast integral with the frog, can be provided with chairs and lugs such as shown at *i*, *j*, *m*, *n*. But it is generally sufficient to connect the stock rails such as *e'*, *f'* (Figs. 6 and 7) with the frog point rails *a'*, *b'* by the usual fish plates, these joints undergoing considerably less stress than the other joints of the frog (ends of the bent rail *a* and curved rail *b*).

The ends of the frog near rails *a'* and *b'* are provided with rather short point guard rails *g'*, *h'*, cast with the rest of the crossing.

These point guard rails *g'*, *h'* constitute the beginning of the guard rails *i'*, *j'*, independent of the frog and of which the length and the grooves *k'*, *l'* are such that the last wheel of a vehicle of small base or of a bogie of a vehicle with a large wheel base, of which the first arrives at the end *m'* (Fig. 8), of the point *b'*, is still in the narrowest part of the groove *h'*, in order to ensure that the vehicle is efficiently guided on entering the crossing.

The guard rails *i'*, *j'*, on which the wheels never run, can be maintained in the prolongation of the point guard rails *g'*, *h'* by members independent or not of the crossing, so as to allow their positions to be adjusted as may be required. They are provided with apertures at their extremities *n'*, *o'*, in the usual manner.

In order to increase the longitudinal stability of the crossing, flanges, such as *p'*, *q'*, are provided cast at the ends of the point guard rails *g'*, *h'*, and the rails, such as *k* and *l*, in the prolongation of the bent rail *a*, are bolted to these flanges.

The crossing can be constructed so that the thickness of the metal is as uniform as possible, as shown in Figs. 3 and 5 and indicated at *r'* and *s'*, but, obviously, other webs, reinforcements or the like can be added which may be useful to ensure a good construction.

In the appended claims I intend to mean by "guiding length" the length along which the groove above referred to is so narrow as to provide for an effective guiding.

What I claim is:

1. A railway frog for slip switches comprising a bent rail, a curved rail adapted to join switch rails of the slip switch two frog point rails, one at each end of said frog, chairs near the ends of the bent rail and of the curved rail, lugs located above said chairs adapted to engage the webs of the rails that are fixed upon them, said lugs providing a recess between them and the chairs for the flanges of the last mentioned

rails, all these elements being cast in a single unit, and bosses on the chairs for preventing the rails from moving in the lateral direction.

2. A railway frog for slip switches comprising a bent rail, a curved rail adapted to join switch rails of the slip switch two frog point rails, one at each end of said frog, a guard rail intermediate said bent rail and said curved rail, a solid web located at a relatively high level for connecting said guard rail to said curved rail, chairs near the ends of the curved rail and of the bent rail, lugs located above said chairs adapted to engage the webs of the rails that are fixed upon them, said lugs providing a recess between them and the chairs for the flanges of the last mentioned rails, all these elements being cast in a single unit, and bosses on the chairs for preventing the rails from moving in a lateral direction.

3. A railway frog for slip switches comprising a bent rail, a curved rail adapted to join switch rails of the slip switch two frog point rails, one at each end of said frog, a bent guard rail extending from one end of the frog to the other end and intermediate said bent rail and said curved rail, a solid web located at a relatively high level for connecting said guard rail to said curved rail, two point guard rails, one at each end of said frog, adapted to cooperate with said bent rail, chairs near the end of the bent rail and of the curved rail, lugs located above said chairs adapted to engage the webs of the rails that are fixed upon them, said lugs forming a recess between them and the chairs for the flanges of the last mentioned rails, all these elements being cast in a single unit, and bosses on the chairs for preventing the rails from moving in the lateral direction.

4. A railway frog for slip switches comprising in combination a bent rail, two frog point rails, one at each end of the frog, a bent guard rail extending from one end of the frog to the other and raised above the level of the other rails of the frog, and a curved rigid rail for connecting switch rails of the slip switch, all these elements being cast in a unitary structure.

5. A railway frog for slip switches comprising in combination a bent rail, two frog point rails, one at each end of the frog, a bent and raised guard rail extending from one end of the frog to the other end, a curved rail for connecting switch rails of the slip switch, chairs near the ends of the bent rail and of the curved rail, lugs located above said chairs adapted to engage the webs of the rails that are to be fixed upon them, said lugs providing a recess between them and the chairs for the flanges of the last mentioned rails, the distance from the upper part of said lugs to said chairs being substantially smaller than the distance from the

under face of the flanges of the rails for which they are adapted to the under side of the head thereof, so that the flanges of the last mentioned rails may rest freely upon 5 said chairs, all these elements being cast in a unitary structure, and bosses on the chairs for preventing the last mentioned rails from moving in the lateral direction.

6. A railway frog for slip switches according to claim 1 in which the distance from 10 the upper part of said lugs to said chairs is substantially smaller than the distance from the under face of the flanges of the rails for which they are adapted to the under side of 15 the head thereof.

7. A railway frog for slip switches according to claim 2 in which said guard rail is bent and raised above the level of the other 20 elements of the frog, and the distance from the upper part of said lugs to said chairs is substantially smaller than the distance from the under face of the flanges of the rails for which they are intended to the under side of the heads thereof.

25 8. A railway frog for slip switches according to claim 3 in which the first mentioned guard rail is bent and raised above the level of the other elements of the frog, and the distance from the upper part of said lugs to 30 said chairs is substantially smaller than the distance from the under face of the flanges of the rails for which they are intended to the under side of the heads thereof.

9. A railway frog for slip switches according to claim 1 further comprising chairs near 35 the ends of the frog point rails, lugs located above said chairs adapted to engage the webs of the track rails that are fixed upon them, said lugs providing a recess between them and 40 the chairs for the flanges of the last mentioned rails, all these elements being cast in a unitary structure, and bosses on the last mentioned chairs for preventing the last mentioned track rails from moving in the lateral 45 direction.

50 10. A railway frog for slip switches which comprises in combination, a bent rail, two frog point rails, one at each end of the frog, a bent guard rail extending from one end of 55 the frog to the other end thereof, and a curved rigid rail for connecting switch rails of the slip switch, all these elements being cast in a unitary structure.

55 11. A railway frog for slip switches, which comprises in combination, a bent rail, two frog point rails, one at each end of the frog, a bent guard rail extending from one end of the frog to the other end thereof, a curved rigid rail for connecting switch rails of the 60 slip switch, and means, integral with said curved rail for rigidly securing thereto said switch rails, all these elements being cast in a unitary structure.

65 12. A railway frog for slip switches, which comprises in combination, a bent rail, two

frog point rails, one at each end of the frog, a bent guard rail extending from one end of the frog to the other end thereof and raised above the level of the other rails of the frog, a curved rigid rail for connecting switch rails 70 of the slip switch, a solid web located at a relatively high level for connecting said guard rail to said curved rail, and means, integral with said curved rail, for rigidly securing thereto the switch rails, all these 75 elements being cast in a unitary structure.

In testimony whereof I have signed this specification.

PIERRE MARIUS GROSJEAN.
